ELECTRICAL TESTING INSTRUMENT

John T. Armbruster, Niagara Falls, N.Y., assignor to
American Optical Company, Southbridge, Mass.

Filed Oct. 12, 1961, Ser. No. 67,054

Term of patent 14 years

(Cl. D26—5)

FIG. 1 is a perspective view of an electrical testing instrument, showing my new design; and

FIG. 2 is a side elevational view thereof, partly broken away and in cross-section.

The back of the cabinet is plain and the side opposite to that shown is substantially a mirror image of the side shown in FIG. 1.

I claim:

The ornamental design for an electrical testing instrument, as shown and described.
